UNITED STATES PATENT OFFICE.

JAMES LA TOURETTE, OF ST. LOUIS, MISSOURI.

PUMP-BUCKET.

SPECIFICATION forming part of Letters Patent No. 276,695, dated May 1, 1883.

Application filed October 25, 1882. (No model.)

To all whom it may concern:

Be it known that I, JAMES LA TOURETTE, of St. Louis, Missouri, have made a new and useful Improvement in Pump-Buckets, of which the following is a full, clear, and exact description, reference being had to the annexed drawings, making part of this specification, in which—

Figure 1 is a side elevation, partly in section, of a pump-bucket having the improvement; Fig. 2, a bottom view of the bucket; and Figs. 3 and 4, top views of the rod-straps, the position of the rod being indicated by the broken lines. In Fig. 3 but one of the straps bears upon the rod. In Fig. 4 both of the straps are in place.

The same letters of reference denote the same parts.

The present invention relates more especially to the mode of connecting the rod-straps with the other parts of the construction.

A represents the packing of the buckets. It is secured to the rings, B C. The rings are provided with the flanges *b c*, respectively, the flanges flaring, and the packing at its lower edge being held between the flanges. The rod D is attached to the straps E E'. The straps, at their lower ends, pass through and are secured to the rings B C, each strap having a flange, *e*, which bears upon the upper side of the upper ring, B, and the end *e'* of the strap below the ring C being threaded to receive a nut, F. The tightening of the nut draws the rings B C together, serving both to fasten the rod straps to the rings and also to clamp the packing between the ring-flanges. In pump-buckets of the kind under consideration the rod-straps in use are apt to work loose in the rings. To obviate this difficulty and to enable the rod-straps to be properly secured to the rings of the bucket, the nuts F are made in the form of lock-nuts—that is, the nuts have shoulders or projections *f*, and the ring C, on its under side, is provided with projections *e'*. The projections of the ring, after the nuts have been tightened against the ring, come in the way of the projections or shoulders of the nuts, and the nuts, in consequence, are prevented from unscrewing.

The operation of connecting the various parts of the bucket is as follows: The packing being between the ring-flanges, the straps are passed through the rings B C, and the nuts are screwed onto the ends of the straps; 55 or, rather, as the nuts, by reason of the ring projections *e'*, cannot be rotated, the straps are screwed into the nuts, and after the nuts have been thus tightened against the ring C the rod D is attached to the straps by means 60 of the bolts G, substantially as shown in Fig. 1. It is necessary for the straps, when tightened upon the rings, to be turned so as to bring the upper ends of the straps properly 65 against the rod, as shown in Fig. 4; but generally, when the straps are first tightened upon the rings, it will be found that the straps, at their upper ends, are not turned toward the rod, but are at an angle therewith, as indicated by the position of the strap E', Fig. 3. 70 The procedure then is to loosen the strap in the nut and to turn the nut around upon the strap suitably to correspond to the angle at which the strap diverges from the rod, whereupon the strap is again tightened to the rings 75 B C and the bolts G passed through and properly secured to the straps and rod. It is an advantage to have the nuts furnished with several projections, *e'*, as thereby the straps can be more readily and effectually adjusted 80 and tightened to the rings and rod.

I claim—

1. In a pump-bucket, the combination of the packing A, the rings B and C, respectively having as an integral part the flanges *b* and *c*, 85 the rod D, and straps E E', screw-threaded on their lower ends, *e'*, and locked by nuts F, substantially as described.

2. In a pump-bucket, the rings C *c*, of a single piece, and having projections *e'*, the rod-straps E E', screw-threaded on their ends *e'*, and shouldered nuts F *f*, substantially as described.

JAMES LA TOURETTE.
